UNITED STATES PATENT OFFICE.

FRANK OSTROWSKY, OF NEW YORK, N. Y.

DESIGN FOR A SLIPPER.

No. 39,412.

Specification for Design.

Patented July 7, 1908.

Application filed May 25, 1908. Serial No. 435,002. Term of patent 14 years.

To all whom it may concern:

Be it known that I, FRANK OSTROWSKY, a subject of the Empire of Russia, residing at New York city, in the county of New York and State of New York, have invented a new, original, and ornamental Design for Slippers, of which the following is a specification, reference being had to the accompanying drawing, forming part thereof.

The figure is a perspective view of a slipper showing my new design.

I claim:

The ornamental design for a slipper, as shown.

FRANK OSTROWSKY.
